United States Patent Office

Des. 217,828
Patented June 16, 1970

217,828

HOLDER FOR A BEVERAGE CAN OR THE LIKE

Lester E. Hilliard, 1709 45th St.,
Des Moines, Iowa 50311

Filed June 10, 1968, Ser. No. 12,282

Term of patent 14 years

Int. Cl. D7—99

U.S. Cl. D44—29

FIG. 1 is a perspective view of a holder for a beverage can or the like showing my new design;

FIG. 2 is a front elevational view thereof;

FIG. 3 is a side elevational view thereof as viewed from the left-hand side of FIG. 2;

FIG. 4 is a top plan view thereof; and

FIG. 5 is a bottom plan view thereof.

I claim:

The ornamental design for a holder for a beverage can or the like, substantially as shown.
